UNITED STATES PATENT OFFICE.

CLYDE L. CRAIG, OF WASHINGTON COURT HOUSE, OHIO.

FLOAT-VALVE.

1,349,267.

Specification of Letters Patent. Patented Aug. 10, 1920.

Application filed January 18, 1917. Serial No. 143,071.

To all whom it may concern:

Be it known that I, CLYDE L. CRAIG, a citizen of the United States, residing at Washington Court House, in the county of

5 Fayette and State of Ohio, have invented certain new and useful Improvements in Float-Valves, of which the following is a specification, reference being had to the accompanying drawings.

10 This invention relates to certain improvements in float valves and it is an object of the invention to provide a device of this general character having novel and improved means whereby the float may be

15 caused to ride upon the surface of the water or to be submerged to any predetermined extent in accordance with the particular requirements of practice.

Furthermore it is an object of the invention to provide a novel and improved device of this general character whereby the float may be maintained submerged so that the same will be protected against interference which would possibly be imposed 25 thereupon by the elements, such as wind, snow, ice, or the like in the event the boat should ride upon the surface of the water.

A still further object of the invention is to provide a device of this general character 30 including a float operatively engaged with the valve member together with a balancing member operatively engaged with the valve member for controlling the position of the float relative to the water level so that said 35 float may be caused to ride upon the surface of the water or be submerged to any predetermined depth when the valve member has been seated to close the water supply.

40 It is an object of the invention to provide a novel and improved device of this general character including a buoyant body operatively engaged with a weighted valve member whereby the valve will be caused 45 to work against the pressure of the water supply when the buoyant body is not in action so that the buoyant body may be submerged before the water supply is completely cut off.

50 The invention consists in the details of construction and in the combination and arrangement of the several parts of my improved float valve whereby certain important advantages are attained and the device is rendered simpler, less expensive and

otherwise more convenient and advantageous for use, all as will be hereinafter more fully set forth.

The novel features of the invention will hereinafter be definitely claimed.

In order that my invention may be the better understood, I will now proceed to describe the same with reference to the accompanying drawings, wherein is disclosed a view partly in elevation and partly in 65 section illustrating a float valve constructed in accordance with an embodiment of my invention, a coacting tank being shown in fragment.

As disclosed in the accompanying drawings, T denotes a tank of predetermined dimensions and for any particular purpose. Arranged within the tank T at any desired point and preferably adjacent the bottom thereof is the stand pipe 1 in communication with a suitable source of water supply. Positioned within the stand pipe 1 is the valve member 2 which is adapted to control the discharge of the water through the pipe 1 into the tank T.

Operatively engaged with the valve member 2 is the stem 3 which, as herein disclosed, is vertically extended above the upper or discharge end of the stand pipe 1, and the free end portion of the stem 3 is 85 returned, as indicated at 4, and then extended laterally, as at 5, said laterally extended portion 5 being of such a length as required by the necessities of practice.

Slidably mounted upon the portion 5 is 90 the poise 6 of predetermined weight and which is fixed in its different positions upon the portion 5 through the medium of the binding screw 7. At this time I wish to state that I do not wish to be understood 95 as limiting myself in any way as to the character of the poise 6 or the manner whereby said poise is mounted or adjusted relative to the portion 5 of the stem 3, although in practice I have found that the 100 arrangement hereinbefore described and as illustrated in the drawings serves with a maximum of efficiency.

The returned portion 4 of the stem 3 affords a loop or eye which permits a suitable connection with the stem 3 of the flexible member M of a predetermined length and which has its outer end portion suitably connected to the buoyant body or float 8.

The buoyant body or float 8 may be of any desired material or construction but as herein disclosed said buoyant body or float 8 consists of a hollow metallic member.

5 The adjustment of the poise 6 serves to control the position of the buoyant body or float 8 relative to the water level within the tank T when the discharge through the stand pipe 1 has been closed. It will be
10 understood that when the poise 6 is positioned at the inner end of the portion 5 of the stem 3, the buoyant body or float 8 will ride upon the surface of the water when the flow through the stand pipe 1 is completely stopped. However, it is of especial import that the float or buoyant body 8 be submerged especially when the tank is of such a character as to be employed in the open, as for agricultural or stock purposes. It
20 is thought to be self-evident that when the float or buoyant body 8 is submerged no interference is offered thereto by the elements, such as wind, snow, or ice.

25 The depth to which the float or buoyant body 8 will be submerged can be readily regulated by the extent of outward adjustment of the poise 6 upon the portion 5 of the stem.

30 When the float or buoyant body 8 is at nearly the limit of its upward movement, the member M will serve as a fulcrum for the stem 3. The poise 6 carried by the portion 5 of the stem 3 initially maintains the stem 3 angular relative to the longitudinal
35 axis of the stand pipe 1 upon the rise of the water level in the tank and when the float or buoyant body 8 has rendered the member M substantially taut and the member 8 is at nearly the limit of its upward movement
40 the marginal portion of the valve 2 will contact with a portion of its seat arranged at the top of the stand pipe 1. The force of the water passing upwardly through the stand pipe 1 will coact with the valve to
45 gradually overcome the resistance of the poise 6 and completely force the valve 2 into closed position. The period of time however, required to completely close the valve member 2 permits the discharge of a
50 sufficient amount of water within the tank 2 to submerge the float or buoyant body 8. The water escaping from the stand pipe 1 will also exert additional pressure upon the disk 9, to be hereinafter referred to, or direct
55 upon the float or buoyant body 8 whereby the proper closing of the valve member 2 is further assured.

60 I also find it of advantage in practice to suitably fix to the stem 3 at a predetermined point exterior of the stand pipe 1 the disk 9, said disk being of such diameter as to obstruct the flow of water as discharged from the pipe 1 and deflect the water so that the water as discharged will not be thrown
65 above the tank T. The use of this disk 9

is of particular advantage when the stand pipe 1 is in communication with a source of water supply of high pressure, such as main pressure.

Interposed in the stand pipe 1 below the 70 valve member 2 is the check valve 10 herein disclosed as of a flat type and provided at its axial center with the weight 11 to facilitate the maintenance of said check valve 10 in its closed position.

75 The use of the check valve is of importance when a plurality of tanks are employed and in connection with a common source of water supply and wherein said tanks are at different levels as it will at once 80 be self-evident that the water within the tank T will be held therein should a second tank at a lower level be emptied.

85 From the foregoing description, it is thought to be obvious that a float valve constructed in accordance with my invention is of an extremely simple and comparatively inexpensive nature and is particularly well adapted for use by reason of the convenience and facility with which it may be assembled, 90 and it will also be obvious that my invention is susceptible of some change and modification without material departure from the principles and spirit thereof and for this reason I do not wish to be understood 95 as limiting myself to the precise arrangement and formation of the several parts herein shown in carrying out my invention in practice, except as hereinafter claimed.

100 It will also be at once apparent that the poise 6 or its mechanical equivalent will serve to operate or prevent the valve member 2 being held in closed position under the influence of the water pressure passing through the pipe 1 when the buoyant body 105 or float 8 is not in action as the poise 6 serves to tilt the valve member 2 against the water pressure.

I claim:

1. In combination with a valve member 110 and its seat, a buoyant body operatively engaged with the valve member, and means for retarding the seating of the valve member under the influence of the buoyant body to submerge the buoyant body before the 115 valve member is in close contact with its seat.

2. In combination with a valve member and its seat, a buoyant body operatively engaged with the valve member, and means carried by the valve member for retarding the seating of the valve member under the influence of the buoyant body to submerge the buoyant body before the valve member is in close contact with its seat.

120 3. In combination with a valve member and its seat, a buoyant body operatively engaged with the valve member, and adjustable means for retarding the seating of the valve member under the influence of the 130

buoyant body to submerge the buoyant body before the valve member is in close contact with its seat.

4. In combination with a valve member and its seat, a buoyant body operatively engaged with the valve member, and means for maintaining the buoyant body in submergence when the valve member is in closed contact with its seat.

10 5. In combination with a valve member and its seat, a buoyant body operatively engaged with the valve member, a lateral extension carried by the valve member, and a poise adjustably engaged with the extension.

6. In combination with a valve member and its seat, a buoyant body operatively engaged with the valve member for moving it against its seat, a lateral extension carried by the valve member, and means coacting with the lateral extension for retarding the seating of the valve member.

In testimony whereof I hereunto affix my signature in the presence of two witnesses.

CLYDE L. CRAIG.
